DENTAL FLOSS HOLDER

James R. Griffin, Plainview, Tex.

Application May 20, 1958, Serial No. 50,990

Term of patent 14 years

(Cl. D24—1)

FIG. 2

The characteristic features of my design reside in the head member having the configuration shown.

I claim:

The ornamental design for a dental floss holder, as shown and described.
